JACOB STEHMAN'S
Halo Photograph Printing
Apparatus.

75482

PATENTED

MAR 10 1868

UNITED STATES PATENT OFFICE.

JACOB STEHMAN, OF LANCASTER, PENNSYLVANIA.

PHOTOGRAPHIC-PRINTING APPARATUS.

Specification forming part of Letters Patent No. 75,482, dated March 10, 1868.

To all whom it may concern:

Be it known that I, JACOB STEHMAN, of Lancaster, in the county of Lancaster and State of Pennsylvania, have invented a new and Improved Mode for Producing Portrait-Like Cabinet-Photographs, by means of a secondary printing process and appliances; and I do hereby declare that the following is a full and exact description thereof, reference being had to the accompanying drawings, making a part of this specification, in which—

Figure 1 is a perspective view of my halo-printing apparatus; Fig. 2, the oval, roundly, or otherwise beveled disk or halo-formator; Fig. 3, a profile view of the same, with its central column or handle and cord-supporter; Fig. 4, a covering-screen, of ground glass-ware, tissue-paper, or other transparent medium, to produce a diffused reflection of transmitted light, round or oval in form, or otherwise, to produce the result.

The nature or object of my invention consists in producing a new style of photographs, which I call the "cabinet-portrait style," presenting a beautifully-graduated halo around the figure, reversing the vignette style, by having the outer edges dark, from any shade to a jet black, instead of the glaring white margin, so easily soiled, and inclined to turn into a dirty yellowish color in time.

To enable others skilled in the business or art to make and use my invention, it is only necessary to say that I procure a smooth board, of the desired size, raised from the table by short feet or strips beneath, to facilitate the handling.

F represents this printing-board, and f the ledges across the bottom. G are four spring or turning clamps, to hold the picture P.

The halo-formator A has a central flat disk, B. This covers the face and high lights of the picture, previously printed by the ordinary printing process in vogue for vignette photographs. The outer portion of the formator A is rounded or beveled to a thin edge around the circumference, be the form oval, circular, or otherwise. The central column or perforated handle c is affixed to the beveled formator A, of any desired length.

Gum-elastic cords D D' are passed through the perforations in the top of the column, crossing each other at right angles, each end of the cords terminated by a loop or its equivalent, to attach over a headed nail,

knob E, or its equivalent, which stays the combined halo-formator A B C in its position, and admits of its being easily handled, as well as turned up to change the pictures, with the greatest facility.

In order that the same handle c may be applied to variously-shaped formators A, I use a bolt with a head countersunk into the center of the disk or formator A, with a nut on the screw end of the bolt to fasten the same. I also find it convenient to use gum cords, stretched across the printing-board F, parallel to each other, from one corner to the other, under which the plate and paper are readily slipped and held in place. By the use of beveled oblong slots, these cords can be adjusted nearer to or more remotely from each other, in place of the clamps G, shown in the drawing.

The operation will be understood by the foregoing description of the apparatus employed—that is, as fast as the photographs are printed in the ordinary manner they are placed at P, on the printing-board F, the halo-formator A B C adjusted, and the light will strike around and more diffused or scattered under the beveled disk A. By judicious handling and exposure to the action of the light, the effect can be varied from a light halo, deepened more or less at pleasure, to suit the taste of the operator, and the most beautiful and softened gradations can be produced by this appliance, not to be reached by any other process heretofore in use, and introduces a new style of cabinet-pictures to the public, highly appreciated by persons of taste.

I am aware that pictures presenting a kind of halo are produced by placing a darkened diaphragm in front of the lens, either in or before the camera. This gives, usually, unsatisfactory results, and differs substantially from my additional printing process, which I believe new, and never before used. I therefore do not broadly claim the halo surrounding photographs, but the combined secondary printing-frame, with or without a screen, H. What I claim as my invention, and desire to secure by Letters Patent, is—

The additional printing process, substantially in the manner specified.

JACOB STEHMAN.
